UNITED STATES PATENT OFFICE

99,095

DESIGN FOR A CONTAINER CLOSURE

James W. Perry, Hartford, Conn., assignor to Colt's Patent Fire Arms Manufacturing Co.,
Hartford, Conn., a corporation of Connecticut

Application January 6, 1936, Serial No. 60,451

Term of patent 14 years

To all whom it may concern:

Be it known that I, James W. Perry, a citizen of the United States, residing at Hartford, in the county of Hartford, and State of Connecticut, have invented a new, original, and ornamental Design for a Container Closure, of which the following is a specification, reference being had to the accompanying drawing.

Of the drawing:

Fig. 1 is a top view of a container closure embodying my new design.

Fig. 2 is a side view.

I claim:

The ornamental design for a container closure as shown.

JAMES W. PERRY.
